UNITED STATES PATENT OFFICE

159,108

TANK TRUCK

Clifford Brooks Stevens, Milwaukee, Wis., assignor to La Crosse Trailer Corporation, La Crosse, Wis., a corporation of Wisconsin

Application June 17, 1949, Serial No. 3,358

Term of patent 14 years

(Cl. D14—3)

To all whom it may concern:

Be it known that I, Clifford Brooks Stevens, a citizen of the United States, residing at Milwaukee, in the county of Milwaukee and State of Wisconsin, have invented a new, original, and ornamental Design for a Tank Truck, of which the following is a specification, reference being had to the accompanying drawing, forming part thereof.

Fig. 1 is a front and side perspective view of the tank truck, showing my new design; and

Fig. 2 is a rear and side perspective view thereof.

The characteristic features of my design reside in the portions shown by means of full lines in the drawing.

I claim:

The ornamental design for a tank truck, substantially as shown and described.

CLIFFORD BROOKS STEVENS.
